(57) **CLAIM**

The ornamental design for the decorative brewer, as shown and described.

DESCRIPTION

FIG. 1 is an isometric view of the decorative beverage brewer of this invention;

FIG. 2 is a front view thereof;

FIG. 3 is a rear view;

FIG. 4 is a right side view, the left side view being a mirror image thereof;

FIG. 5 is a top plan view;

FIG. 6 is a bottom view;

FIG. 7 is a second embodiment of the decorative beverage brewer, all sides the same as the first embodiment except the control panel; and,

FIG. 8 is a third embodiment of a decorative beverage brewer, all sides being the same as the first embodiment except that the upper tier is removed.
